UNITED STATES PATENT OFFICE.

RICHARD A. HEILENDAY, OF JERSEY CITY, NEW JERSEY, ASSIGNOR TO STANDARD OIL DEVELOPMENT COMPANY, A CORPORATION OF DELAWARE.

COMBINED TANK CLOSURE AND GAUGE.

Application filed December 31, 1926. Serial No. 158,381.

This invention relates to improvements in combined tank closures and gauging devices. The invention will be fully understood from the following description read in connection 5 with the accompanying drawing, in which

Fig. 1 is a vertical section through the improved tank closure, the section being taken on the line II—II, Fig. 2;

Fig. 2 is a top plan view of the closure; 10 and

Fig. 3 is a perspective view of the closure cap and gauge stick.

In the drawings, reference numeral 1 denotes a metallic filling neck exteriorly 15 threaded at its ends. The lower end of the neck 1 is screwed into or otherwise fastened upon a tank or other container; the upper end receives an internally screw threaded collar 2. An outwardly extending flange 3, 20 having perforations 4, is formed on the collar. A cap 5 has a screw connection with the top of the collar 2. A flange 6 on the cap has perforations 4' and overlies the flange 3. A wire or flat seal 7 passes through 25 cooperating perforations 4, 4'. The ends of the wire are brought together and held by a metallic wafer 8. When flat seals are used they may be secured together by a sealing press or pliers.

30 The cap 5 has a cylindrical boss 9 on which is screwed a cover 10. A gauge stick 11 has a metallic hanger 12 secured to the upper end of the stick. A rivet or screw 13 fastens the hanger rotatably on the cover 10. The 35 boss 9 has an opening 14, rectangular in cross section, through which the gauge stick passes. Angle pieces 11' are riveted or otherwise secured to the bottom of the gauge stick, making it impossible to completely remove 40 the stick from the cap. The opening 14 is therefore obstructed at all times and liquid can not be introduced or withdrawn through it.

45 A gasket 15 makes a fluid-tight seal between the collar 2 and the cap 5. The gasket is firmly held inside the cap 5 by reason of the undercutting of the cap threads. The neck and collar may be secured together by

a rivet or screw 16, or these parts may be integral.

50 In the use of the device, a container, for example an underground gasoline storage tank, is filled through the neck 1, on which the collar 2 is screwed and securely held by rivet or screw 16. The cap 5 with cover 10 and gauge stick 11 attached is screwed on the collar until the cap is firmly tightened against gasket 15. The perforations 4, 4' are so positioned on flanges 3 and 6 that a sealing device may be readily passed through 55 a pair of perforations 4, 4'. When this has been done, it is impractical to put in or take out substantial quantities of liquid without breaking the seal. Tampering with the contents of the tank is avoided in this way. 60 Sealing as described, however, does not prevent the gauging of the tank. The cover 10 may be unscrewed and its attached gauge stick 11 examined whenever it is desired to know how much liquid is in the tank. 65

I claim:

1. In combination with the filling neck of a container, an exterior flange about said neck, a cap for said neck and having an opening therein, an exterior flange on said cap, 75 means for sealing flanges against unauthorized opening, a cover for the opening in said cap, and a gauging stick carried by the cover and depending through the filling neck.

2. Apparatus according to claim 1, in which the flange about the neck is carried by a collar screwed on the neck.

3. A closure for the filling neck of a container, and comprising a neck-engaging 85 member having an external flange, a cap for said member and having also an external flange, means for sealing said flanges against unauthorized opening, a threaded boss on the cap fitted with a central opening, a cover arranged to screw over said boss, a gauging stick sliding through the opening and substantially filling the same, said stick being fastened to the cover and fitted with projections to prevent removal of the stick through 90 the opening in the cap.

4. In combination with the filling neck of a container, a cap for the neck, visible means for sealing the cap to the neck, said cap having an opening therein, a cover for said opening, a gauging stick fastened to the cover operable thru said hole and substantially closing the same and means on the stick to prevent its complete removal.

5. The combination as claimed in claim 4 in which the cap is provided with a central, 10 externally threaded boss, and said cover is in the form of a cap internally threaded and adapted to screw over said boss.

In testimony that I claim the foregoing as my invention, I affix my signature.

RICHARD A. HEILENDAY.
